US00D737150S

(12) United States Design Patent
Tilahun(10) Patent No.: US D737,150 S
(45) Date of Patent: * Aug. 25, 2015(54) PACKAGE

- (71) Applicant: Kraft Foods Group Brands LLC,
Northfield, IL (US)
- (72) Inventor: Muluken Tilahun, Waunakee, WI (US)
- (73) Assignee: Kraft Foods Group Brands LLC,
Northfield, IL (US)
- () Term: 14 Years
- (21) Appl. No.: 29/507,628
- (22) Filed: Oct. 29, 2014
